UNITED STATES PATENT OFFICE.

ALBERT DUNAND, OF PARIS, FRANCE.

APPARATUS AND SYSTEM FOR TELEPHONIC COMMUNICATION.

SPECIFICATION forming part of Letters Patent No. 280,365, dated July 3, 1883.

Application filed January 9, 1883. (No model.) Patented in France December 14, 1880, No. 140,133.

To all whom it may concern:

Be it known that I, ALBERT DUNAND, a citizen of the French Republic, residing in Paris, France, have invented certain Improvements 5 in Apparatus and Systems for Telephonic Communication, of which the following is a specification.

The possibility of reproducing sounds by the action of the undulatory current of a microphone on an electric condenser has long been 10 known.

My present invention has for its object to reproduce speech by means of electric condensers, and in particular "singing condensers," so called. To this end I place the condensers on the secondary circuit of an induction-coil, in which circuit a battery is also installed, and in the primary circuit thereof is included the usual battery and microphonic 20 transmitter.

Figure 1 of the accompanying drawings is a diagram showing the electrical installation of my system. Fig. 2 is an elevation of one of my singing-condensers. Fig. 3 is a transverse 25 section of the same on a larger scale. Fig. 4 is a diagram illustrating the arrangement of the leaves in the condenser. Figs. 5 and 6 show the preferred form of grouped condensers, each view being a section cut in the plane 30 of the like-numbered line in the other. Fig. 7 is a horizontal section of a modified form of condenser. Fig. 8 is a front elevation of another form, and Fig. 9 is a transverse section thereof.

Let B in Fig. 1 designate an induction-coil, of which $p\ p$ is the circuit in connection with the primary wire thereof, and $s\ s$ the circuit in connection with the secondary wire thereof. In the primary circuit $p\ p$ are installed a battery, P, and a microphonic transmitter, M, whereby the current from this battery, passing through the primary wire of the coil, is undulated upon speech being uttered in the proximity of the transmitter, as is well understood.

In the secondary circuit $s\ s$ are installed another battery, P' , and a condenser, C. This condenser is preferably constructed as shown in Figs. 2 and 3, and may be square, circular, or oblong, with a width or diameter of about 50 six centimeters, and containing about thirty or forty leaves of tin-foil. Thus constructed

and installed it reproduces speech with perfect clearness, and sufficiently loud to be easily heard when applied to the ear. This result is due to the intercalation of the battery P' in 55 the secondary circuit, as it is the polarization of the condenser due to the potential of this battery which renders the condenser capable of reproducing articulate sounds.

The leaves of tin-foil $a\ a$ of the condenser are 60 united alternately, two by two, in such a manner as to form two series, each connected to one of the binding-posts $b\ b$, which are mounted on the box c , in which the leaves are inclosed. In the front of this box is an opening, e , to 65 facilitate the escape of the sound. The leaves of tin-foil are separated from each other by the interposition of sheets of insulating material, $d\ d$ —for example, leaves of ordinary paper or of paraffined or varnished paper. These are 70 shown only in Fig. 4, where they are denoted by dotted lines, the full lines denoting the leaves of foil. The best arrangement, however, is to use two of these condensers, united in derivation in the circuit $s\ s$, so that in listening one may be placed over each ear. 75

When it is desired to obtain much more intense sounds, which may be heard at some distance, I combine in one box, as shown in Figs. 5 and 6, a number of condensers—say 80 five or six, or more, if necessary—and connect them either in series or in derivation, but preferably in derivation. The condensers are arranged parallel, but slightly separated from each other, as shown in Fig. 5, all the armatures on one side being connected together and joined to one binding-post b , while all those on the other side are likewise united and joined to the opposite binding-post. At one side of their inclosing-box A, at a little distance from 85 the edges of the condensers, is an opening, E, to which one ear of the listener may be applied, while from a corresponding opening on the opposite side an acoustic tube, F, may be conducted to his other ear. Another arrangement consists in placing the condensers so that they shall touch each other at their rear edges, while their front edges are separated about a centimeter, after the manner of a fan, as shown in Fig. 7. The rear edges may be mounted on 90 a platform or sounding-box, D. Thus constructed, it is not necessary to apply the ear 95

to the condensers, as the sound may be heard at a distance of several meters. Another method is shown in Figs. 8 and 9. Five condensers are arranged in a quadrangular form, 5 the fifth serving as a base, whereby a sort of box is formed, open in front, which by its form sends the sound to a considerable distance.

My condensers are made with a thin leaf or 10 plate, *f*, of sonorous and resisting material—such as card-board, hard rubber, glass, celluloid, metal, &c.—which may be pierced with a central opening or not, as desired.

My system is not restricted in its application 15 to the precise details and methods herein set forth and shown, but may be applied to batteries, microphones, and condensers of any kind, size, or shape.

I claim as my invention—

20 1. The improved system of telephonically transmitting sound, which consists of the com-

bination of an induction-coil, a primary circuit including the primary wire thereof, a microphonic transmitter and a battery, both included in said circuit, a secondary circuit 25 including the secondary wire of said coil, and a battery and condenser, both included in said secondary circuit, substantially as set forth.

2. The combination, to form a receiving-telephone, of several singing-condensers grouped 30 together, with intervening spaces to facilitate the escape of sound, and with the opposite armatures of all the condensers connected with opposite terminals, substantially as set forth.

In witness whereof I have hereunto signed 35 my name in the presence of two subscribing witnesses.

ALBERT DUNAND.
